UNITED STATES PATENT OFFICE.

ROBERT MCNEIL, OF ALLEGHENY, PENNSYLVANIA.

STREET-SWEEPER.

SPECIFICATION forming part of Letters Patent No. 583,710, dated June 1, 1897.

Application filed January 27, 1897. Serial No. 620,895. (No model.)

To all whom it may concern:

Be it known that I, ROBERT MCNEIL, a citizen of the United States of America, residing at Allegheny, in the county of Allegheny and 5 State of Pennsylvania, have invented certain new and useful Improvements in Street-Sweepers, of which the following is a specification, reference being had therein to the accompanying drawings.

This invention relates to certain new and useful improvements in sweepers, and relates more particularly to that class employed as street-sweepers, and has for its object to construct a sweeper of the above-described 15 class that will be extremely simple in its construction, strong, durable, effectual in its operations, and comparatively inexpensive to manufacture; furthermore, to construct a sweeper and scraper combined that may be 20 easily operated and attached to an ordinary broom, if so desired.

A still further object of the invention is to construct a combined sweeper and scraper which will admit of a new sweeper being 25 readily placed in position and also the replacing of the scraping-blade, if necessitated.

With the above and other objects in view the invention finally consists in the novel construction, combination, and arrangement 30 of parts to be hereinafter more specifically described, and particularly pointed out in the claims.

In describing the invention in detail reference is had to the accompanying drawings, forming a part of this specification, and 35 wherein like letters of reference indicate similar parts throughout the several views, in which—

Figure 1 is a perspective view of my improved sweeper and scraper. Fig. 2 is a plan view of one of the dividing-rods, showing the 40 hangers in perspective. Fig. 3 is a perspective view of the binding-bar. Fig. 4 is a perspective view of the ferrule and plate for attaching the handle to the sweeper.

Referring now to the drawings by reference-letters, *a* indicates the frame, consisting of a bar bent at right angles near such end to form the sides of the frame, said sides having compound bends *c c* to form the flat portions *d d*, to which is attached the scraping-blade *b*.

Extending in alinement with the bar *a* is a binding-bar *e*, shutting against the side pieces of the frame and held in position by bolts *ff*, secured in the bar *a*, said bolts carrying 55 hangers *g g*, which carry in their lower ends the dividing-rods *h h*, having forwardly-bent ends *h' h'* to engage and hold the sweeping material of the sweeper. Secured to the rear face of the bar *a* at its center is a plate 60 *k*, carrying a ferrule or socket *l*, which receives the handle *m*, said plate being preferably secured by bolts through the bar *a*, so that the same can be removed and bolted onto the bar *e* through the apertures *e' e'*, thus 65 allowing the sweeper to be used in the reverse manner when one side becomes worn.

The sweeping material used for the sweeper (which is referenced *n* and shown in dotted lines in Fig. 1) is secured between the bar *a* 70 and the binding-bar *e*, said binding-bar being securely fastened against the sweeping material by means of the bolts and nuts through the said bars, this sweeping material being divided as in the usual construction of brooms 75 and the like by means of the dividing-rods *h h*, the curved ends of which engage over the ends of the sweeping material and retain same firmly in place.

When the sweeper has become worn, a new 80 one may readily be inserted by loosening the binding-bar and filling the frame again in the same manner.

To use the scraper, the sweeper is inverted, which brings the sharp or cutting 85 edge of the blade *b* in contact with the pavement.

It will be noted that various changes may be made in the details of construction of my improved sweeper and scraper without departing from the general spirit of my invention. 90

Having fully described my invention, what I claim as new, and desire to secure by Letters Patent, is—

1. In a sweeper a frame, a scraper carried by said frame, adjusting-bolts engaging the frame, and carrying binding-bar, sweeping material, held by the said binding-bar, dividing-rods suspended from the bolts, said dividing-rods holding the sweeping material, substantially as shown and described. 95 100

2. In a sweeper, a frame, a binding-bar within said frame, said bars supported by bolts engaging the rear bar of the frame, hangers on said bolts, dividing-rods carried by said hangers, and a suitable handle attached to the frame, substantially as shown and described.

In testimony whereof I affix my signature in presence of two witnesses.

ROBERT MCNEIL.
